(57) **CLAIM**

The ornamental design for a display screen or portion thereof with graphical user interface, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever. This application is a continuation of Co-pending U.S. patent application Ser. No. 29/533,436, filed Jul. 17, 2015, of which the entire contents of both applications are hereby incorporated by reference herein.

The FIGURE is a front view of a display screen or portion thereof with graphical user interface.

The outer broken line rectangle showing the display screen or portion thereof and all other broken lines showing portions of the graphical user interface are included for the purpose of illustrating portions of the article and form no part of the claimed design.

The broken lines illustrating text, lines, numbers and images in the drawing show portions of the graphical user interface that form no part of the claimed design.
